UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

ART OF ATTACHING HEELS.

Application filed October 24, 1921. Serial No. 509,820.

This invention relates to methods of attaching shoe heels and is concerned particularly with attaching heels of the multi-section type, a typical example of which is the 5 conventional rubber half heel combined with a leather or leatherboard base section.

It has heretofore been proposed to attach heels of the type referred to at a single operation of the heel nailing machine, the 10 leather base and rubber lift being assembled on the heel seat of a shoe and the load of attaching nails being driven at a single blow through both the rubber and base sections until their heads were seated on the usual 15 washers embedded in the rubber and their points clinched in the innersole of the shoe. Single nailed, multi-section heels have heretofore been open to the drawback that when it became time to repair the heel by removing 20 the rubber lift and attaching a new one the leather base section would drop off when the rubber lift was removed because all the attaching nails passed through washers in the rubber lift, and consequently they were 25 all pulled out in the act of removing the rubber lift. This happening was objectionable, not only because of the extra time required to replace and attach the heel base before the new rubber heel was applied but even more 30 so because it spoiled the finish of the heel edge and was liable to leave a crack at the junction of the heel base and the outer sole.

The object of the present invention is to overcome the difficulties above described and 35 to provide a novel method of so attaching a multi-section, or composite, heel that the rubber lift may be removed, leaving the base attached to the shoe. For the accomplishment of this object the invention provides a 40 method of heel attaching which comprises pressing upon a shoe a heel base and a rubber top section having washers embedded therein, and driving simultaneously to the same depth a plurality of attaching nails, 45 some of which pass through said washers and some of which do not. This method makes possible a virtually separate attachment of the base although all the attaching nails may be of the same length. In the 50 illustrative example of the invention hereinafter described part of the fastenings, viz., the nails designed primarily to attach the heel base to the shoe, are located in portions of the rubber heel where there are no wash-

ers, while the heads of the remaining nails 55 are anchored in washers, the heads of all the nails lying at substantially the same depth in the rubber. As is well known, the nails have no substantial holding power in the rubber in the absence of washers or their 60 equivalent and, therefore, when the rubber heel is removed only those nails will be pulled out which pass through the washers. In a heel attached by the method of this invention it may be considered that the attaching nails are divided into two groups, 65 that is to say, those whose primary function it is to secure the heel base permanently to the shoe and which are substantially effective only for that purpose, and those 70 which serve the primary purpose of attaching the rubber lift and, incidentally, add security to the attachment of the base. The nails of the first-mentioned group, at least, may, advantageously, taper somewhat from 75 head to point to afford additional holding power, although this is not essential to the invention.

Other features and advantages of the invention will be understood and appreciated 80 from reading the following detailed description in connection with the accompanying drawings, in which

Figure 1 is a view partly in perspective and partly in section of a composite heel attached to the heel end of a shoe;

Fig. 2 shows a conventional type of heel- 85 ing machine equipped to attach heels in accordance with the invention; and

Fig. 3 is an enlarged detail illustrating 90 more clearly the relation of the elements at the end of the nail driving operation.

Referring now to the drawings, a composite heel is shown consisting of a base section 10, which may be made of leather, 95 leatherboard or like material, and a rubber lift, or half heel, 12 superposed upon the base 10. The heel consisting of the two sections above described is located upon the heel end of the outersole 14 of the shoe and the whole assemblage is secured together by 100 nails 16 driven through and clinched in the innersole 18.

The usual washers 20 are embedded in the rubber heel section and slight indentations 105 22 may be provided on the tread face thereof to indicate the points at which the base attaching nails are to be driven. The nails

are preferably tapered from head to point, as shown, and are all driven to the same depth, as clearly illustrated in Fig. 3. No washers are located beneath the indentations 5 and consequently the base attaching nails, while they hold the base 10 securely to the shoe by reason of the friction between them, and the relatively rigid material of the base 10, and the tapered shape of the nails, are 10 not substantially effective in securing the rubber section 12, the nails which pass through the washers 20 being depended upon for this although sufficient of the head ends 15 of the base attaching nails remains permanently in the rubber section to reduce very materially the lateral shifting of the yielding rubber back and forth upon the base, which occurs to a detrimental degree each time the weight of the wearer comes upon a 20 rubber heel of the washer type attached by relatively few nails.

When it is desired to remove the rubber lift 12 it may be pried off, pulling out the 25 nails which pass through the washers 20, while the rubber strips easily off the heads of the remaining nails, leaving the latter unmoved and leaving the base 10 undisturbed. The projecting heads of the last-mentioned 30 nails may then either be clipped off or the new rubber lift forced upon them, and the usual attaching nails may be driven to secure the new rubber section to the base.

Referring particularly to Fig. 3, 24 indicates an improved form of nail driver which 35 is sharpened at the point 26 where it engages the head of the nail 16. The pressure required to drive the nail is sufficient to cause the point 26 to indent the nail head, and any sidewise bending of the nail in the 40 soft substance of the rubber 12 is effectually prevented. The portion 28 of the driver is also tapered toward the sharpened point, permitting the driver to enter the substance of the rubber lift 12 smoothly without lacerating the rubber. This minimizes the 45 defacement of the rubber lift by the driver, the mark remaining after the driver is withdrawn being insignificant.

It should be clearly understood that the 50 word "rubber", used herein in referring to

the heel section 12, is used in an inclusive, rather than in a definitive sense and is intended to include all the known equivalents commonly used in the manufacture of cushion heels. Likewise the word "leather", 55 used in referring to the base section 10, should be understood to include leatherboard and other equivalents, of which such heel bases are made.

Having described the invention, what is 60 claimed as new and desired to be secured by Letters Patent is:—

1. That method of attaching a heel to a shoe which comprises pressing upon the shoe a heel base and a rubber top section having washers embedded therein, and driving simultaneously to the same depth a plurality of attaching nails, some of which pass through said washers and some of which do not. 70

2. That method of attaching a heel to a shoe which comprises pressing upon the shoe a heel base and a rubber top section having washers embedded therein, and driving simultaneously a plurality of attaching nails 75 of equal length, some of which pass through said washers and some of which do not.

3. That method of attaching a heel to a shoe which comprises pressing upon the shoe a heel base and a rubber top section, and 80 then driving to the same depth at a single operation a plurality of attaching nails, certain of said nails being substantially effective to attach only the heel base to the shoe and others of said fastenings being fully 85 effective to attach the top section to the shoe.

4. That method of single nailing a heel base and a rubber heel section of the washer type to a shoe which consists in assembling the shoe and heel parts and then simultaneously driving through both parts of the heel and the shoe, with a heel nailing machine, a plurality of heel attaching nails all of the same length in such positions that part of said nails pass through the washers of the 90 rubber section and the remainder of said 95 nails do not pass through said washers.

In testimony whereof I have signed my name to this specification.

JOSEPH H. POPE.
